UNITED STATES PATENT OFFICE.

EDMUND A. CURTIS, OF CHICAGO, ILLINOIS.

DESIGN FOR A CAR-TRUCK FRAME.

SPECIFICATION forming part of Design No. 32,930, dated July 10, 1900.

Application filed June 7, 1900. Serial No. 19,475. Term of patent 14 years.

To all whom it may concern:

Be it known that I, EDMUND A. CURTIS, a citizen of the United States, residing at Chicago, in the county of Cook and State of Illinois, have invented and produced a new and original Design for Car-Truck Frames, of which the following is a specification, reference being had to the accompanying drawings, in which—

Figure 1 is a side elevation of a car-truck frame embodying my design, and Fig. 2 is a plan view of the same.

The novel feature of my design consists in the configuration of the car-truck frame, the same being composed of two parallel side members 1, each comprising an upper member 2 and a lower member 3, which are parallel throughout the greater portion of their

length and which have their extremities curved or bent toward each other to a meeting, as indicated at 4. The united ends of the side members are joined at each end of the frame by a transverse member 5, which has its ends inclined to their points of junction with the side members. Each lower member of the side frames comprises an arch 6, located near each of its ends and extending upward to and embracing the upper member of the side frame.

I claim—

The design for a car-truck frame substantially as shown and described.

EDMUND A. CURTIS.

Witnesses:

IRVINE MILLER,

FREDERICK C. GOODWIN.
